UNITED STATES PATENT OFFICE.

JAMES P. NIEMANN, OF BROOKLYN, ASSIGNOR TO JOHN W. FOULKS, OF NEW YORK, N. Y.

WHIP-SOCKET.

SPECIFICATION forming part of Letters Patent No. 325,562, dated September 1, 1885.

Application filed April 28, 1885. (No model.)

To all whom it may concern:

Be it known that I, JAMES P. NIEMANN, of Brooklyn, in the county of Kings and State of New York, have invented a new and useful Improvement in Whip-Sockets, of which the following is a specification.

This invention relates to whip-sockets, and has for its object to provide a whip-socket with a rubber, which is detachable, and which is held firmly in position by its own conformation as will be fully explained hereinafter.

In the accompanying drawings, which form part of the specification, my invention is fully illustrated, letters of reference being used to indicate corresponding parts throughout the drawings.

Figure 1 represents the top end of a whip-socket with my improved rubber *a* attached. Fig. 2 represents the same with the rubber *a* removed, showing the transverse slots *c*, through which the rubber is inserted. Fig. 3 represents a top view of the rubber *a*, showing the inwardly-projecting pieces *e*, which are adapted to fit in the slots *c*, as will be herein-after described; and Fig. 4 represents a section through the line *xx*, Fig. 3, showing in cross-section one of the pieces *e*, and the groove *d* on the lower side of the same.

Rubbers that have been applied to whip-sockets heretofore, as a rule, have been attached to the interior of the socket, and in a short time become loosened and useless. It will be easily understood that my improved rubber and socket overcomes this difficulty, and that the rubber is beyond any possibility of being removed by the whip.

As shown at Fig. 2, the upper end of the whip-socket is provided with three (3) transverse slots, *c*, leaving sections of the material between the slots of sufficient strength to hold

the top of the socket firmly, the material of which the socket is made being usually of thin metal. The rubber, as shown at Figs. 3 and 4, is made to form a flat band with three flat sections, which are thinner than the width 45 of the band, extending inwardly toward the center, the inner edges of these pieces *e* combined to form a circle which is the requisite size to admit and hold the whip in place. On the lower side of the pieces *e*, close to the band 50 portion of the rubber, is a channel or groove, *d*. These grooves are for the purpose of giving more elasticity to the pieces *e*, which will permit the whip to be withdrawn more freely.

The rubber is stretched over the top of the 55 whip-socket with the groove *d* side down. The inwardly-projecting pieces are fitted in the transverse slots *c*, and the invention is complete, and will have the appearance similar to that shown in Fig. 1.

Having thus described my invention, what I claim, and desire to secure by Letters Patent, is—

1. A whip-socket provided with the transverse slots *c*, and a rubber adapted to be inserted from the outside to hold the whip in position, as described and specified.

2. A whip-socket provided with the transverse slots *c*, in combination with the rubber constructed, as described, with the inwardly-projecting pieces *e*, all as described, and for the purpose herein set forth.

In testimony that I claim the foregoing improvement in whip-sockets, as above described, I have hereunto set my hand this 2d day of 75 January, 1885.

JAMES P. NIEMANN.
